UNITED STATES PATENT OFFICE.

WILLIAM P. DALRYMPLE, OF CHICAGO, ILLINOIS, ASSIGNOR TO CHICAGO STEEL WHEEL CO., OF CHICAGO, ILLINOIS, A CORPORATION OF ILLINOIS.

WHEEL.

1,418,069.

Specification of Letters Patent. Patented May 30, 1922.

Application filed August 28, 1919, Serial No. 320,357. Renewed October 13, 1920. Serial No. 416,778.

To all whom it may concern:

Be it known that I, WILLIAM P. DALRYMPLE, a citizen of the United States, and a resident of Chicago, in the county of Cook and State of Illinois, have invented certain new and useful Improvements in Wheels, of which the following is a specification, reference being had to the accompanying drawings.

10 My invention relates to wheels and it has for its principal object the provision of a new and improved form of wheel in which the hub is connected to the rim by sheet metal plates and in which improved means 15 is employed for securing the rim in position and for producing the desired tension upon the parts. It is another object of my invention to improve the form and construction of wheels of this type in sundry 20 details hereinafter pointed out. The preferred means by which I have accomplished my several objects are illustrated in the accompanying drawings and are hereinafter 25 specifically described. That which I believe to be new and desire to cover by Letters Patent is set forth in the claims.

In the drawings:

Fig. 1 is a side view of a wheel embodying my improved construction.

30 Fig. 2 is a vertical cross-section upon an enlarged scale taken upon the line 2—2 of Fig. 1.

Fig. 3 is an enlarged detail being a section upon line 3—3 of Fig. 2.

35 Fig. 4 is a view, partly in section, showing the wedge construction employed for expanding the rim.

Fig. 5 is a bottom plan view of the fragment of structure shown in Fig. 4.

40 Fig. 6 is a central vertical section taken substantially on line 6—6 of Fig. 4.

Fig. 7 is a perspective view of the wedge employed for holding the rim in expanded condition.

45 Fig. 8 is a view similar to Fig. 6, but showing a modified form of construction.

Fig. 9 is a bottom plan view of the parts shown in Fig. 8, being partly in section taken on line 9—9 of Fig. 8.

50 Figs. 10, 11, 12, 13 and 14 are vertical cross-sections through rims of slightly modified construction.

Referring to Figures 1 to 7 inclusive, in which corresponding parts are indicated by

the same reference characters,—20 indicates 55 the inner hub of my improved wheel provided with a cap 21 secured thereon by means of screw threads serving to hold the outer hub 22 in position through the medium of a diagonally disposed flange 23 against 60 which the cup 21 abuts, the two hub members having a diagonally disposed bearing upon each other at one end for insuring proper co-operation. A sleeve 24 is slidably mounted upon the outer hub 22 upon 65 which it is adapted to be adjusted by means of a screw threaded ring 25 which abuts against the end of the hub 22. As will be readily understood, the parts 22 and 24, together with the adjusting ring 25, comprise 70 in effect an adjustable outer hub member. Sheet metal parts 26 and 27, which in the construction shown are in the form of discs, are interposed as hereinafter described between the outer hub member and the rim 75 28. As is shown in Fig. 2, the rim 28 comprises, in the construction shown, a collapsible flange part 29 engaging a suitable groove in one edge of the part 28, for assisting in holding demountably in position, a pneumatic tire 30 of any suitable type.

The sheet metal web portions 26 and 27 are, in the construction shown, secured to the outer hub member by means of annular 85 flanges 31 which engage tapered ring portions 32 forming parts of the outer hub member. Split rings 33 are mounted within the flanges 31 of the web portions, such rings being tapered upon their outer faces to correspond to the interior taper of the tapered ring portions 32, as is best shown at the bottom of Fig. 2. The rings 32 are adapted to be expanded for forcing the flanges 31 into snug engagement with the rings 32 90 by means of screws 34 having tapered heads 35 adapted to abut against the beveled ends of the ring 33, as is clearly shown in Fig. 3, the screws 34 being held in position by supports upon the adjacent portions of the 100 outer hub member. As will be readily understood, when the split ring 33 has been once expanded serving to force the flange 31 of the web 26 into engagement with the tapered ring portion of the outer hub member, the web member is secured permanently in position with respect to the outer hub member, being incapable of being detached 105

therefrom upon the subsequent collapsing of the split ring 33.

The connection of the sheet metal parts 26 and 27 with the rim 28 so as to make the rim easily demountable in the construction shown, comprises interengaging hooks which can be brought into and out of operative engagement as may be desired. As is shown in Fig. 2, each of the sheet metal parts 26 and 27 is provided at its outer periphery with an annular hook 36, such hooks engaging hooks 37 upon the inner face of the rim 28, the hooks 37 in the construction shown being formed integrally with the rim. As is shown in Figs. 5 and 6, the rim 28 is cut out at one point so as to provide for the collapsing of the rim. As will be readily understood, when the ends of the rim are drawn together serving to reduce the effective diameter of the circular rim 28, the annular hooks 36 can be moved into or out of engagement with the hooks 37 of the rim, and the rim can be moved out of position on the wheel. When, however, the rim 28 is again placed in position and expanded by forcing the ends of the rim apart, the effective diameter of the rim is increased, placing a tension upon the hooks 36 and 37 and upon the sheet metal parts 26 and 27.

My preferred means for expanding the rim 28 comprises a suitable means for forcing the ends of the rim 28 apart. In Figs. 4 to 7 inclusive, I have shown a wedge construction for accomplishing this result. A wedge 38, beveled at its edges, as is best shown in Fig. 6, is inserted between the ends of the rim 28 and driven in until the desired expansion of the rim is secured. Seats are preferably formed upon the end portions of the rim in diagonal position therein, as is shown in Fig. 5, by means of lugs 39 struck down from the material of the rim, the end portion of each of such lugs being beveled so as to hold the wedge 38 in position, as is best shown in Fig. 6. As is also shown in this figure, the seats for the wedge 38 are preferably reinforced by suitable welding as indicated at 40 in said Fig. 6. The wedge 38 is adapted to be held in position by means of having its end portion 41 forced into engagement with the flange 29, being further supported in this position by means of a machine screw 42 having screw-threaded connection with the flange 29.

Referring to Figs. 8 and 9 which show a modified form of means for expanding the rim, 43 and 44 indicate pins journaled between the flanges of the hooks 37 of the rim 28, such pins being connected together by means of a double-acting screw 45 provided upon its central portion with a worm gear 46 which is operated by means of a worm 47 secured in position in any suitable manner.

Referring to Figs. 10 to 14, each of which

shows a modified form of structure, it will be seen that in Fig. 10 a double hook 48 is employed upon the rim 28 in place of the two separate hooks of the construction first described. In Fig. 11, the hooks 37 are formed upon a band 49 secured to the rim 28 by means of rivets 50 instead of being formed integrally with the rim as in the construction first described. In Fig. 12 a single hook 51 is employed adapted to receive both of the hooks 36 of the sheet metal discs 26 and 27. In Fig. 13 a single hook 52 is adapted to receive the hook 53 of a sheet metal web 54 of a heavier weight adapted by itself to support the hub with reference to the rim. In Fig. 14 a piece of resilient material 55 is inserted between the hook 53 of the web and the hook 52 of the rim.

By the use of my improved construction, I have provided that any given portion of the rim may have in effect a free inward sliding movement with respect to the hub, whereby the hub may be supported by the base 54 or by either one of the plates 26, 27, in concentric position with respect to the upper portion of the rim, while at the same time the lower portion of the rim is permitted to give upwardly under the influence of the weight carried by the hub.

While I have shown the rim in Figs. 13 and 14 as being supported by the single plate 54 formed of a single sheet of metal, I desire to have it understood that I do not wish to be restricted to the formation of such single plate in integral form from a single sheet of metal, but that on the contrary, the term "single plate" is used in the specification and claims to designate a single supporting disc structure, to distinguish from the double plate construction, as illustrated in the remaining figures in which two plates, 26 and 27, are employed in spaced relation to each other so as to give an effective double support for the hub.

So far as I am aware, I am the first in the art to provide for securing a wheel rim in position about the hub by expanding the rim so as to bring cooperating hooked parts into operative engagement and my claims are to be construed to cover this expedient broadly, whether in the form of wheel shown in the drawings or in any other form. While I prefer to mount the rim demountably in position, it will be understood that I do not restrict myself to the use of that type of structure except in so far as the claims are specifically limited to a construction of that character. I wish it also to be understood that in my use of the term "rim" in the specification and claims I do not limit myself at all to the form of rim shown in the drawings which directly supports the tire, but rather refer broadly to a band or equivalent part at the periphery of the wheel which either by itself or in connection with other parts forms the

member upon which the hub is supported by the spokes or equivalent structure. While I have illustrated in some of the drawings the use of two plates or heads 26-27 supporting the hub with respect to the rim, I do not desire to be restricted to this construction except as hereinafter specifically claimed, inasmuch as it is evident from an inspection of Fig. 2 that each of the plates 26-27 acts entirely independently of the other plate. Since either plate could be removed entirely without affecting the arrangement or operation of the other, it is evident that either plate is adapted by itself by hooked engagement with the rim to support the hub.

What I claim as my invention and desire to secure by Letters Patent, is—

1. A wheel comprising in combination a hub, a rim, and a sheet metal plate adapted by itself by hooked engagement with said rim to support said hub.

2. A wheel comprising in combination a hub, a rim, and two sheet metal plates having hooked engagement with said rim, either of said two plates being adapted by itself by its hooked engagement with the rim to support said hub independently of the other plate.

3. A suspension type wheel comprising a hub, a rim, and a sheet metal disc secured about said hub and connected with said rim, and adapted by itself to support the hub from the rim, the connection between the disc and the rim being such as to permit inward movement of the rim with respect to the disc, while at the same time preventing outward movement of the rim beyond normal position with respect to the disc.

4. A suspension type wheel comprising a hub, a rim, and a sheet metal disc connecting said hub with said rim and serving by itself to support the hub in concentric position with respect to the upper portion of the rim, at the same time permitting free movement of the lower portion of the rim towards the hub.

5. A wheel comprising in combination a hub, a rim, and a rigidly-dished sheet metal plate adapted by hooked engagement with said rim to support said hub.

6. A wheel comprising in combination a hub, a sheet metal plate having operative engagement with said hub and having a hook at its margin, and a rim having a hook on its inner face held by expansion of the rim in snug engagement with the hook of said plate.

7. A wheel comprising in combination a hub, an expandable rim, and connections between said hub and said rim adapted to be placed under tension by the expansion of said rim.

8. A wheel comprising in combination a hub, an expandable rim, connections between said hub and said rim adapted to be placed under tension by the expansion of said rim

and adapted to be disengaged from the rim when the rim is again collapsed, and means carried by the rim for expanding the rim.

9. In a wheel, the combination of a hub member, an expandable rim member, connections between said two members comprising a sheet metal part having hooked connection with one of said members, and means for expanding said rim member for placing said connections under tension. 75

10. In a wheel, the combination of a hub member, an expandable rim member, a rigid sheet metal disc suitably secured to said hub member and having hooked engagement with said rim member, and means for expanding said rim member serving to place said sheet metal disc under tension. 80

11. In a wheel, the combination of a hub member, an expandable rim member comprising a hook extending about its inner face, a sheet metal disc suitably secured to said hub member and provided with an annular hook about its periphery adapted to be brought into engagement with the hook of said rim member when the rim member is collapsed, and means for expanding said rim member serving to place said disc under tension. 85

12. A wheel comprising in combination a hub, a rim broken at one point for permitting expansion of the rim, connections between said hub and said rim adapted to be placed under tension by the expansion of said rim, and means acting upon the end portions of said rim for expanding the same. 95

13. A wheel comprising in combination a hub, a rim broken at one point for permitting expansion of the rim, connections between said hub and said rim adapted to be placed under tension by the expansion of said rim, 105 and a wedge adapted to be inserted between the end portions of said rim for expanding the rim.

14. A wheel comprising in combination a hub, a rim broken at one point for permitting expansion of the rim, connections between said hub and said rim adapted to be placed under tension by the expansion of said rim, lugs struck down and reinforced in the end portions of said rim providing diagonally-disposed seats, and a wedge adapted by co-operation with said seats to expand said rim. 115

15. In a wheel, the combination of a hub member, an expandable rim member, two sheet metal discs each suitably secured to said hub member and each having hooked engagement with said rim member, and means for expanding said rim member serving to place both of said sheet metal discs under tension. 120

16. In a wheel, the combination of a hub member, an expandable rim member comprising two hooks extending about its inner face and opening away from each other, two sheet metal discs each suitably secured to said hub member and each provided with an annular 125

hook about its periphery, the hooks of said discs being adapted to be brought into engagement with the hooks respectively of said rim member when the rim member is collapsed, and means for expanding said rim member serving to place both of said discs under tension.

17. A wheel comprising in combination a hub, a collapsible rim member, and a sheet metal plate adapted by an expansion of the rim to be given a firm hooked engagement with said rim member and adapted by itself by such hooked engagement to support said hub.

18. In a wheel, a metal disc having a central hub opening provided with a marginal flange, a hub provided with a conical flange decreasing in diameter toward its free edge and adapted to receive the flange on said disc, and means for expanding said disc flange within said hub flange to a conical form corresponding with said hub flange.

19. In a wheel, a metal disc having a central hub opening provided with a marginal flange, a hub provided with a conical flange decreasing in diameter toward its free edge and adapted to receive the flange on said disc, and a locking ring having an outer conical surface corresponding to that of said hub flange for expanding and locking said disc flange against said hub flange.

20. In a wheel, a metal disc having a central hub opening provided with a marginal flange, a hub provided with a circular flange, the inner surface of which is conical and decreases in diameter toward its free

edge and adapted to receive therein said disc flange, an expanding locking ring having an external conical surface corresponding to 40 that of the hub flange, said ring adapted to be expanded to expand the disc flange into conical form corresponding to the hub flange and to lock the former against the latter.

21. In a wheel, a metal disc having a 45 central hub opening provided with a marginal flange, a hub provided with a circular flange, the inner surface of which is conical and decreases in diameter toward its free edge and adapted to receive therein said disc 50 flange, a split locking ring having an external conical surface corresponding to that of the hub flange, and a wedge for expanding said ring so as to expand said disc flange into 55 conical form corresponding to the hub flange and to lock the former against the latter.

22. In a wheel, the combination of a hub member, a rim having means whereby it may be expanded in diameter, an intervening structure comprising a pair of metal discs, 60 secured to said hub, and means for operatively connecting said intervening structure to the rim by expansion of said rim.

23. In a wheel, the combination of a hub, a rim, an intervening structure comprising 65 a metal disc having a continuous surface secured to the hub and detachably connected to the rim, said rim being severed transversely adapting it for disengagement from the rest of the wheel, and means for placing said 70 intervening structure in tension between said hub and rim.

WILLIAM P. DALRYMPLE.
